ROAD JOINT FORMER AND LOAD
DISTRIBUTOR

Robert R. Robertson, Chicago, Ill., assignor to
The Translode Joint Company, Chicago, Ill., a
corporation of Illinois

Application September 6, 1932, Serial No. 631,875

26 Claims. (CL 94—18)

The present invention relates to an improved type of expansion or contraction joint holder and load distributor adapted to be supported transversely on a road sub-grade to serve as a convenient means for supporting or holding expansion fillers, cracking plates, removable cores or the like supported in position to permit concrete to be poured to imbed the holders and fillers and form the top or crown section of a road having expansion joints at spaced intervals in the length of a road separated by intermediate contraction or cracking joints. The improved expansion joint former consists of shiftable filler holders which are movably disposed in a grooved base member which serves not only as a guide member for the holders but also acts as a guard for preventing water, silt and dirt from working upwardly into the expansion joint.

It is an object of this invention to provide an expansion joint holder and load distributor adapted to be imbedded transversely in a road or similar concrete construction to hold expansion or contraction joint fillers or cores in position and serve as a means for distributing the load across the joint from one road section to another.

It is also an object of this invention to provide an expansion joint holder comprising a grooved guide base for movably receiving flanged holding sections in staggered relation on opposite sides of an expansion joint filler or core to hold the same in position transversely of a road to form an expansion joint adapted to serve as a load distributing means between adjacent sections of the road.

It is a further object of this invention to provide an improved type of expansion joint holder and load distributor consisting of load distributing sections adapted to be shiftable positioned within a guide base which serves as a means for preventing upward seepage of water and silt around the expansion joint fillers or cores supported by the load distributing sections thereby obviating the widening of the expansion joints.

It is furthermore an object of this invention to provide an expansion or contraction joint device comprising flanged sections provided with extensions and having the flanged portions thereof movably engaged in a grooved base member provided with a closed bottom to prevent seepage of water and silt around the joint fillers or cores to prevent widening of the expansion and contraction joints.

It is an important object of this invention to provide an improved type of expansion or contraction joint holder and load distributor includ-

ing shiftable sections engaged in staggered relation on opposite sides of a filler or core, said sections provided with integral anchoring members and with base flanges having shiftable engagement with a guide base formed with a closed bottom which serves as a stop means for preventing the seepage of water and silt upwardly into the expansion or contraction joint thus obviating widening or enlargement of the joint.

Other and further important objects of this invention will be apparent from the disclosures in the specification and the accompanying drawings.

The invention (in a preferred form) is illustrated in the drawings and hereinafter more fully described.

On the drawings:

Figure 1 is a fragmentary top plan view of a concrete road having expansion joints and contraction joints provided transversely at spaced intervals in the road and formed by improved joint forming means and load distributors embodying the principles of this invention.

Figure 2 is an enlarged vertical detail section taken on line II—II of Figure 1 and illustrating the expansion joint holder in position holding an expansion joint filler or core in place.

Figure 3 is an enlarged vertical detail section taken on line III—III of Figure 1 illustrating the adaptation of the joint holder for supporting a road cracking plate in position to form a contraction joint.

Figure 4 is a fragmentary top plan view of the expansion joint holder with the filler or board omitted and illustrating the alternate or staggered positioning of the board holding sections and their engagement in the guide base.

Figure 5 is a side elevation of the expansion joint holder as shown in Figure 4.

Figure 6 is an enlarged end elevational view of the expansion joint holder.

Figure 7 is a fragmentary top plan view of one end of one of the expansion joint holder sections illustrating the projecting means for holding the adjacent ends of the expansion joint holder sections properly spaced to permit transverse shifting movement thereof with respect to the guide base.

Figure 8 is an end elevation of a modified form of an expansion or contraction joint holder and load distributor.

Figure 9 is a fragmentary top plan view of the modified form of the device.

Figure 10 is a vertical detail section of a por-

tion of a road illustrating the modified form of the device including a hollow core removable to permit an expansible filling to be poured into the void.

5. Figure 11 is a vertical detail section of a portion of a road illustrating the modified form of the device used as a contraction joint to cause transverse cracking in the road, and also illustrating means for sealing both the top and bottom of the crack.

10. As shown on the drawings:

15. The reference numeral 1 indicates a concrete road sub-grade having an upper or crown concrete section 2 formed thereon and provided with a longitudinal center joint 3 and with transversely disposed expansion joints 4 separated by a plurality of spaced contraction joints 5.

20. The improved holder and load distributing device embodying the principles of this invention is adapted for use not only in holding expansion joint fillers or cores in place transversely of a road but is also adaptable for use as a contraction joint and load distributing device for holding metal cracking plates in place transversely of a 25 road to cause transverse regular cracking in the upper section or crown of a road.

25. The improved holder comprises an elongated base member consisting of a solid base plate 6 constructed of sheet metal or other suitable material, said base plate having the longitudinal margins thereof deflected upwardly and then inwardly toward one another above the base plate to provide oppositely positioned guide channels 7. The channel portions of the base member provide oppositely positioned guide grooves 8. The top flanges of the channel members 7 are spaced apart to provide a longitudinal top opening in the base member of the device. The grooved or channeled base member is provided in a desired 40 length which may be half of the width of the road or less if preferred. The channeled base member is adapted to be positioned transversely upon the road sub-grade 1 and extends from the side margin of the road to one side of the road center strip 3.

45. Slidably and shiftably engaged in the base member are a plurality of holder sections which are arranged longitudinally in offset or staggered relation with respect to one another. The holder sections are of identical construction with the adjacent sections reversed with respect to one another as clearly illustrated in Figure 4. Each of the holder sections is constructed of metal and comprises a T bar consisting of a base flange 9 and a central web or holding plate 10 integrally formed longitudinally upon the top of the base flange 9. The upper margin of the web 10 is cut to provide a plurality of spaced notches 11 and the material from said notches is bent outwardly to provide anchoring blades or wings 12. The notches 11 are so cut that the lower edges of the blades or wings 12 are inclined so that the outer ends of the blades are wider than the inner ends to form wedge shaped anchoring blades. In case the holder section is of a length which will not permit a full length blade to be formed at one end of the holder section the web 10 is cut downwardly along the edge 13 and the material between said edge 13 and the end of the web is bent downwardly at substantially right angles to form an extra anchoring blade or wing 14. Both the blades 12 and 14 project outwardly from one side of the web 10 leaving the opposite side of the web 10 flat as clearly illustrated in 75 Figure 6.

The holder sections are shiftably and slidably mounted within the base section, with adjacent holder sections reversed with respect to one another so that the blades or wings 12 and 14 project outwardly leaving the flat side of the web 5 10 positioned adjacent the center of the holder providing staggered flat supports and a holding groove or socket 15 for the reception of an expansion joint board or filler 16 which extends from the side margin of the road inwardly toward one 10 side of the center strip 3. The expansion board or filler 16 is constructed of composition material, fiber board or other suitable material and extends upwardly to position the upper edge of the expansion board substantially flush with the 15 top surface of the road to form the expansion joint 4. As illustrated in Figure 1 the expansion joints 4 are positioned at spaced intervals along the length of the road and the space between the expansion joints is divided into road sections 20 by means of the contraction joints 5 which are formed by the use of metal cracking plates 17 (Figure 3) which are supported in position by means of the staggered holders which are moved closer together or closer towards the center of 25 the base strip to hold the metal cracking plates supported in position. The cracking plates 17 are so positioned that the upper edges thereof are located a few inches below the top surface of the road allowing the road to crack substantially in a straight line transversely of the road to form the cracks or grooves 5 which divide the road into sections and eliminate the uneven and promiscuous cracking of the road.

30. After the expansion joint holders and the contraction joint holders are in position upon a road sub-grade the concrete is poured onto the sub-grade to completely imbed the holders and the expansion boards and cracking plates as illustrated in Figures 2 and 3 of the drawings. With 40 the setting of the concrete the holders are anchored or secured in position in the road sections by means of the anchoring blades or wings 12 and 14. It will be noted that the adjacent T sections are anchored in opposite sections of the 45 road and that the T sections are consequently allowed to be moved toward and away from the expansion strip or board 16 with the expansion and contraction of the road sections due to temperature changes. The base flange of each T 50 sections has one half thereof projecting across the joint into an adjacent section of the road thereby affording an arrangement whereby the loads are transmitted across the joint from one road section to an adjacent road section.

55. The adjacent ends of adjacent T sections are prevented from scraping and abutting one another by means of rounded detents or studs 18 one of which is integrally formed on each end 60 surface of the base flange 9 of a holder section. As illustrated in Figure 4 the detents 18 of adjacent holder sections are positioned adjacent one another to hold the end surfaces of the holder sections spaced apart to permit the same to be 65 transversely moved in the base section of the device. When an expansion filler or board 16 is held in position by the holder sections the detents 18 are separated allowing the expansion board to be compressed when adjacent road sections expand. In case the expansion of the road sections is so great that the expansion board 16 is compressed to such an extent that the detents 18 are moved into contact with one another the detents 18 will be sheared off when 70 75.

the webs 10 of the holder sections are moved into substantial alignment with one another.

Figures 8 to 11 illustrate a modified form of expansion and contraction joint device and load distributor comprising a base section of substantially the same construction as that illustrated in the form of the device illustrated in Figures 2 to 6 inclusive. Slidably and shiftably mounted in the guide base section are a plurality of holder sections each comprising an angle bar consisting of a base flange 19 and an upright web or holder plate 20 integrally formed at right angles thereto. The end surfaces of the angle bars are painted with a coating or layer 21 of asphalt paint to avoid friction and permit transverse sliding movement of the holder sections with respect to one another within the base sections. The upper margin of the web or holding plate 20 is cut to provide a plurality of notches. The cut portions of the web are bent outwardly towards the outer side of the device to provide integral anchoring blades or wings 22. The blades 22 project in a direction opposite from the base flange 19. A plurality of the angle holder sections are arranged in each guide base section with the blades or wings 22 projecting outwardly leaving the inner flat surfaces of the web 20 facing inwardly with the base flanges 19 extending across the joints for transmitting loads across the joints. The adjacent holder sections are reversed with respect to one another and are staggered in the base section to provide a central holding groove for the reception of a core unit or plate to hold the same in position transversely of a road.

As illustrated in Figure 10 the holder sections are arranged to support a core unit which consists of a pair of spaced metal plates 23 which extend upwardly above the top of the concrete and are separated by means of a board or wedge 24.

After the concrete is deposited on the sub-grade to imbed the expansion joint forming members, the concrete is allowed to set. The hollow core is then removed and the void or crevass is filled with asphalt or other suitable material to serve as the expansion joint filler.

Figure 11 illustrates an adaptation of the device wherein only the grooved base member and a plurality of the angle-iron holder sections are used to provide a contraction joint forming unit. In this form of the device the slot or opening in the top of the base member is only wide enough to hold the angle sections with the upright webs or flanges 20 in alignment to form a cracking unit to cause formation of a transverse crack 25. The concrete has imbedded therein a grooved crack forming unit 26 positioned directly above the contraction joint device to serve as a top sealer for the crack 25 while the base section 6 acts as a bottom sealer for the crack.

The improved types of expansion and contraction joint devices and load distributors are adapted to be imbedded in concrete with the closed bottoms of the base sections seated on the sub-grade to serve not only as guides for the holder sections but also adapted to serve as sealers or means for preventing seepage of water and silt upwardly in the joints of the road or other concrete constructions in which the devices are adapted for use.

It will of course be understood that various details of construction may be varied through a wide range without departing from the principles of this invention and it is therefore not purposed to limit the patent granted hereon

otherwise than necessitated by the scope of the appended claims.

I claim as my invention:

1. A road joint former and load distributor comprising a channel base section having a closed bottom, a plurality of holder sections shiftably engaged therein in reversed staggered relation and anchoring means struck therefrom.

2. A road joint former and load distributor comprising a base section, a plurality of holder sections movably supported therein with adjacent sections reversed with respect to one another, and means supported in position thereby with said holder sections staggered with respect to one another and engaging opposite sides of said means.

3. A road joint former and load distributor comprising a channeled closed bottom base section, a plurality of holder sections shiftably mounted therein and arranged in staggered relation to provide a holding groove, a filler member supported in said groove with said holder sections alternately arranged to contact opposite surfaces of said filler member, and anchoring members struck from the upper margins of said holder sections for securing the holder sections locked in adjacent sections of a concrete road to permit loads to be distributed between the road sections.

4. A joint former comprising a base section, a plurality of plate holders shiftably engaged in said base section with the plate holders reversed with respect to one another and arranged in staggered relation to provide a plate receiving groove therebetween, spacing means on the ends of the plate holders to obviate friction therebetween, and a plurality of retaining means integrally formed on the plate holders and projecting outwardly therefrom to facilitate anchoring of the plate holders in adjacent sections of a concrete road in which the joint former is imbedded.

5. A concrete joint forming device comprising a base section, a plurality of flanged holder sections shiftably mounted in said base section with alternate holder sections reversed with respect to one another and staggered to provide a plate holding groove therebetween, and a plurality of blade members struck outwardly from the holder sections for anchoring the holder sections in adjacent sections of a concrete road whereby the plate holding groove is adapted to be narrowed and widened with the expansion and contraction of the concrete road sections due to temperature changes.

6. A joint former comprising a grooved base section, a plurality of holders shiftably engaged in said base section with adjacent holders reversed with respect to one another and positioned in staggered relation to provide a receiving groove therebetween, a joint filler seated in said groove with adjacent holders contacting opposite sides of the joint filler, means on the ends of said holders to hold adjacent ends of the holders spaced with respect to one another, said holders having portions thereof notched with the material resulting from the formation of the notches deflected outwardly to provide a plurality of anchoring means permitting the holders to be anchored in adjacent sections of a concrete road to permit the holders to be shifted transversely of the base section to compress the filler when the adjacent road sections are expanded due to temperature changes.

7. The combination with an expansion joint filler, of supporting members therefor arranged

- in staggered relation to contact opposite sides of the expansion joint filler, and a base section constructed to adjustably receive the supporting members to permit the same to be moved toward 5 and away from the filler, said base section having a closed bottom serving as a sealing means to obviate seepage of water and silt upwardly in a road expansion joint formed by the filler.
8. In a road joint former the combination with 10 a filler, of a grooved base member having a closed bottom, and a plurality of holders shiftably mounted in said base member and alternately engaged on opposite sides of the filler to support the same in position.
- 15 9. In a road joint former the combination with a filler, of a passaged base member adapted to be supported on a road sub-grade, a plurality of filler holders shiftably engaged in staggered relation in the base member on opposite sides of the 20 filler, and blade members integrally struck outwardly from the outer sides of said filler holders for anchoring the same in adjacent sections of a concrete road to permit the filler holders to be moved toward or away from the filler with the 25 expansion and contraction of the road sections due to temperature changes.
10. A joint forming device comprising a sealing base, and a plurality of means mounted therein with adjacent means reversed with respect to one 30 another and adapted to be moved in opposite directions into and out of alignment with one another.
11. A joint forming device comprising a sealing base, a plurality of alternately reversed means 35 mounted therein, and anchoring blades struck therefrom for securing adjacent means in opposite concrete sections of a construction in which the device is imbedded.
12. A joint forming device for use in a concrete 40 construction, said device comprising a sealing means, and angle irons alternately reversed with respect to one another and having the supporting flanges thereof slidably engaged in said sealing means and having the remaining flanges projecting upwardly out of the sealing means, and 45 blades struck from said last-mentioned flanges to cause transmission of loads between adjacent concrete sections of the construction.
13. A joint forming device for use in a concrete 50 construction, said device comprising a grooved sealing means, means reversed with respect to one another and engaged therein and including members struck therefrom for anchoring adjacent means in opposite concrete sections of the 55 construction, said means having the base portions thereof alternately staggered and projecting from one concrete section into another to transmit loads between said sections.
14. A load transmission joint comprising a core, 60 a grooved hollow base, and a plurality of angle members transversely shiftable in said base, said angle members positioned in alternating relation on opposite sides of the core and projecting there- beneath into opposite sides of the base.
- 65 15. A load transmission joint comprising a base, a plurality of adjacently positioned reversed supporting means transversely shiftable in said base, and a groove forming core unit supported between said supporting means.
- 70 16. A joint forming device comprising a core section, a closure means thereon, and anchor
- means positioned side by side in reversed staggered relation on opposite sides of the core section and projecting transversely thereof to hold the same in position.
17. A joint forming device comprising a core 5 section, and anchor means positioned side by side in reversed staggered relation beneath the same with adjacent anchor means anchored in opposite sections of a concrete construction and in contact with opposite sides of the core section. 10
18. In a transmission joint of the class de- 15 scribed including an anchoring unit comprising a base means, an angled member slidably engaged therein, and anchoring means on said angled member.
19. A road joint former and load distributor comprising in combination a support including a plurality of reversed staggered supporting means arranged in spaced parallel relation, and a void for 20 ing core unit removably supported thereby. 25
20. A road joint former and load distributor comprising a core unit, and a plurality of anchor means arranged in reversed staggered relation and transversely slidable with respect to the core unit, each of said anchor means comprising a 25 T bar having anchoring members projecting from one side of one of the flanges thereof. 30
21. A joint forming device comprising a core section, a closure means thereon, and spaced parallel anchor means arranged in reversed stag- 35 gered relation with respect to one another and movable transversely of the core section.
22. A road joint former and load distributor comprising in combination a chambered base having a plurality of reversed staggered supporting means projecting therefrom, and a joint forming means removably supported between said means. 40
23. A road joint former and load distributor comprising in combination a base including a plurality of separated supporting means arranged 45 to permit adjacent supporting means to move independently of each other and in opposite directions with respect to one another, and a void forming means supported between the supporting means. 45
24. A road joint former and load distributor including in combination a support having a load transmitting means movably interfitting one side of the same and projecting upwardly out of and over the opposite side of said support for trans- 50 mitting a load from one road section to an adja- cent road section.
25. A road joint former and load distributor including in combination a support having a load transmitting means interfitting the same and 55 transversely shiftable therein, and anchor means on said load transmitting means projecting out of said support for anchoring the load transmitting means in one road section for transmitting a load therefrom to an adjacent road section with which 60 emitting a load from one road section to an adja- cent road section.
26. A road joint former including in combina- 65 tion a base means having a plurality of load trans- mitting means movably engaged therein in par- allel relation with adjacent load transmitting means movable in opposite directions with the expansion and contraction of road sections due to temperature changes. 70

CERTIFICATE OF CORRECTION.

Patent No. 2,027,201.

January 7, 1936.

ROBERT R. ROBERTSON.

It is hereby certified that error appears in the printed specification of the above numbered patent requiring correction as follows: Page 3, first column, line 32, for "on" read one; page 4, secnd column, line 61-62, claim 25, for the syllable and words "mitting a load from one road section to an adjament" read the load transmitting means has slidable engagement; and that the said Letters Patent should be read with these corrections therein that the same may conform to the record of the case in the Patent Office.

Signed and sealed this 3rd day March, A. D. 1936.

Leslie Frazer
Acting Commissioner of Patents.
